UNITED STATES PATENT OFFICE.

JOHN SHUTTLEWORTH, OF ALTRINCHAM, ENGLAND, ASSIGNOR TO LINOTYPE AND MACHINERY LIMITED, OF LONDON, ENGLAND.

SIDE-REGISTER DEVICE FOR PRINTING MACHINES.

Application filed November 6, 1925, Serial No. 67,226, and in Great Britain November 24, 1924.

This invention relates to side register devices for printing machines, of the type in which a pair of feet is reciprocated inwards and outwards transversely of a feed board, 5 and at or near the termination of the inward travel, seize between them a sheet to be registered, and during their outward movement bring the said sheet into contact with the side register stops, and thereafter 10 slide out of engagement with that sheet and move back to starting position.

The object of the invention is to provide an improved construction which shall ensure a more uniformly distributed grip being obtained on the sheet so that the latter shall be less liable to damage or defacement than has heretofore obtained with side register devices as heretofore constructed.

To this end an adjustable bracket which, 20 as heretofore, is reciprocated transversely of the feed board, carries the upstanding stem of the upper side register foot in such a manner that said foot is yieldingly pressed rectilinearly downwards as by a spring acting on the stem (with a pressure which can be adjusted), and can be raised rectilinearly by a cam acting on a pin extending laterally from the stem.

The invention will now be described by 30 reference to the accompanying drawings in which:—

Figure 1 is an elevation of one constructional form of the device as viewed from the feeder side of the printing machine to 35 which it is applied;

Figure 2 is a plan of the device, and

Figure 3 is a front elevation of the pertinent parts of the device as viewed from the underside of Figure 2.

40 For convenience of illustration the device is represented in Figures 2 and 3 as though it occupied a horizontal working position instead of, as it does in practice, an inclined one such as is indicated in Figure 1.

45 The before mentioned bracket 1 is adjustably secured, as by a split sleeve 2 and clamping screw 3, to the register tube 4 which, in the ordinary well-known manner, is longitudinally reciprocated transversely 50 over the feed board 5. Within the bracket 1 is longitudinally slidable the upstanding stem 6 of the upper side-register foot 7 which normally is resiliently pressed downwards by a helical spring 8 encircling the upper reduced end of said stem and at its lower end

bearing on an annular shoulder on the latter. The stem 6 and spring 8 are contained within the tubular part or barrel 1^a of the bracket 1, and, at its upper end the said spring bears against a screw 9 which is adjustable in 60 the barrel for varying the pressure exerted by the spring 8 on the foot 7.

The stem 6 has rigidly attached to it, a pin 10 which extends laterally through a slot or recess 1^b in the lower end of the 65 barrel 1^a and at its outer end is adapted to engage with an inclined pivoted cam 11 by which it is raised antagonistically to the spring 8.

The cam 11 is supported by its pivot 12, 70 in a bracket 13 herein termed a cam bracket which is adjustable along a stationary rod 14 extending transversely over the feed board 5 and can be secured in any desired position thereon by a pinching screw 15. 75 The lowest position of the cam 11 is determined by a stop pin 16 fast in the cam bracket 13 and against which the said cam is normally held by a spring 17 whose upper end bears against a lug 13^a integral with 80 the cam bracket.

The lower side-register foot 18 is secured to the bracket 1 and, as ordinarily, shares with the upper side-register foot 7, the travel transversely of the feed board 5. 85

19 are the side register stops out to which the respective side edges of the sheets are drawn to determine the correct side register, and 20 is a part of one of the inclined sticks on which the sheets are supported during the 90 time that they are drawn by the feet 7, 18 outwards to the side register stops 19.

At the start of the inward travel of the two side-register feet 7, 18, the upper foot 7, is in its lowest position resting upon the 95 lower foot 18 as shown in Figure 3, and, at a later part of this travel, the pin 10 rides over the top of the cam 11 so that the foot 7 is raised rectilinearly so as to pass clearly over the adjacent edge of the sheet to be 100 registered, while, at a still later stage, the pin 10 drops over the inner end of the cam 11 and allows the upper foot 7 to be depressed by the spring 8 on to the sheet to grip it between said upper foot and the lower 105 foot 18. The two feet 7, 18, then start on their outward travel bringing the sheet with them, and during this stage of the operation, the pin 10 passes beneath the cam 11 and 110 tilts it about the axis of its pivot 12 without

itself or the upper foot 7 being affected by this contact of pin and cam, the sheet consequently being drawn outwards to the side register stops 19, after which juncture the 5 continued outward travel of the feet 7, 18 results only in their slippage off the respective edge of the sheet leaving the latter in contact with the said stops.

Having described my invention, I declare 10 that what I claim and desire to secure by Letters Patent is:—

1. In a side register device of the type described for printing machines, the combination with upper and lower side-register feet 15 adapted to grip between them the sheets to be registered, and means for reciprocating in rectilinear direction said feet inwards and outwards transversely of a feed board, of a guide for the upper side-register foot constantly perpendicular to the plane of the sheet to be gripped, by which, movement of said foot relatively to the other foot is restricted to rectilinear direction perpendicular to the plane of the sheet, and a cam 20 adapted to move the upper side-register foot rectilinearly away from the lower one during the mutual travel of the feet in one direction over the feed board and to allow the said upper foot to travel in the reverse direction over the feed board without moving relatively to the lower one.

2. In a side register device of the type described for printing machines, the combination with upper and lower side-register feet 25 adapted to grip between them the sheets to be registered, and means for reciprocating in rectilinear direction said feet inwards and outwards transversely of a feed board, of a guide for the upper side-register foot constantly perpendicular to the plane of the sheet to be gripped, by which, movement of said foot relatively to the other foot is restricted to rectilinear direction perpendicular to the plane of the sheet, and a cam 30 adapted to move the upper side-register foot rectilinearly away from the lower one during the mutual travel of the feet in one direction over the feed board and to allow the said upper foot to travel in the reverse direction over the feed board without moving relatively to the lower one, a spring adapted to bring the upper side-register foot into sheet-engaging relationship with the lower sheet-register foot and, excepting when the 35 cam acts on the said upper side-register foot, to maintain the latter in such relationship.

3. In a side register device of the type described for printing machines, the combina-

tion with a bracket, a lower side-register foot carried thereby and means adapted to reciprocate the bracket inwards and outwards transversely of a feed board, of an upper side-register foot and an upstanding stem thereon longitudinally slidable within the bracket, a spring acting on said stem to 60 yieldingly hold the upper foot in contact with the lower foot, a pin extending laterally from the stem through a slot in the bracket, and a cam in the path of the pin adapted to raise the upper foot against the action of the 65 spring and to allow that foot to be again depressed by the spring, during the inward travel of the bracket.

4. In a side register device of the type described for printing machines, the combination with a bracket, a lower side-register foot carried thereby and means adapted to reciprocate the bracket inwards and outwards transversely of a feed board, of an upper side-register foot and an upstanding stem 70 thereon longitudinally slidable within the bracket, a spring acting on said stem to yieldingly hold the upper foot in contact with the lower foot, a pin extending laterally from the stem through a slot in the bracket, and a pivoted cam in the path of the pin 75 adapted to raise the upper foot and to allow it to be again depressed by the spring during the inward travel of the bracket, and to be tilted about its pivot by the pin during the outward travel of the bracket.

5. In a side register device of the type described for printing machines, the combination with a bracket, a lower side-register 80 foot carried thereby and means adapted to reciprocate the bracket inwards and outwards transversely of a feed board, of an upper side-register foot and an upstanding stem thereon longitudinally slidable within the bracket, a spring acting on said stem to 85 yieldingly hold the upper foot in contact with the lower foot, a pin extending laterally from the stem through a slot in the bracket, a pivoted cam in the path of the pin 90 adapted to raise the upper foot and to allow it to be again depressed by the spring during the inward travel of the bracket, and to be tilted about its pivot by the pin during the outward travel of the bracket, and means 95 adapted to vary the location of the cam along the path of the pin.

In testimony whereof I have affixed my signature hereto.

JOHN SHUTTLEWORTH.
